ELECTRIC RESISTANCE HEATER

Edwin D. Hoyt, Hemet, Calif., assignor to Rama Industrial Heater Co., San Jacinto, Calif.

Filed Apr. 26, 1971, Ser. No. 137,739

Term of patent 14 years

Int. Cl. D23—03

U.S. Cl. D23—77

FIG. 1 is a perspective view of an electric resistance heater showing my new design;

FIG. 2 is a front elevational view of the electric resistance heater on a reduced scale;

FIGS. 3 and 4 are side elevational views thereof;

FIG. 5 is a bottom plan view thereof; and

FIG. 6 is a rear elevational view thereof.

The cord is broken away to indicate indeterminate length.

I claim:

The ornamental design for an electric resistance heater, as shown.
